[57] CLAIM

The ornamental design for a portion of a confectionary package, as shown and described.

DESCRIPTION

FIG. 1 is a top plan view of a portion of a confectionary package embodying my design;

FIG. 2 is another top plan view thereof; and,

FIG. 3 is a third top plan view thereof.

The portion of the confectionary package is of no appreciable thickness and the undisclosed bottom plan view is unornamented. The dashed lines of FIGS. 2 and 3 are to show environment and form no part of the claimed design.
